UNITED STATES PATENT OFFICE.

FRANK A. EPPS, OF NEW YORK, N. Y.; ADDISON O. BONIFACE, OF EAST ORANGE, AND WILLIS D. WITTER, OF ROSELLE PARK, NEW JERSEY, ASSIGNEES, BY MESNE ASSIGNMENTS, TO AMERICAN LA FRANCE AND FOAMITE CORPORATION, A CORPORATION OF NEW YORK.

FIRE-EXTINGUISHING APPARATUS.

Application filed April 1, 1922, Serial No. 548,610. Renewed December 24, 1924.

Our invention relates to fire extinguishing apparatus of the foam type and provides an inexpensive foam system useful especially in the protection of small plants where a complicated and costly installation would be barred. We provide means, whether automatic or manual, for starting siphonic delivery of solutions from the usual acid solution and basic solution containers, solution delivery thereafter being by gravity only and without aid, or at all events without predominating expulsive action, of the starting means, usually a pressure means i. e. a means for changing pressure conditions in the system, and which may therefore be of slight capacity or of only momentary operation, or both, thus reducing expense.

Referring to the drawings:

Fig. 1 is an elevation partly in cross section.

Fig. 2 is an enlarged detail view.

The fire hazard to the protection of which our system is illustrated as applied is an open dip tank 10 containing an inflammable liquid as varnish, lacquer or gasoline. With this tank, in the installation shown, is associated a solution mixing chamber 11 of known type for delivering foam to the surface of the liquid 12 in the dip tank to extinguish the fire. Acid solution container 13 and basic solution container 14 elevated above the dip tank 10, and preferably situated on a higher floor, are each connected to the mixing chamber by connections which are normally open—that is to say they are empty of liquid. These connections are illustrated as comprising the risers 15 and 16 connected respectively at their lower ends to piping 17 and 18, and by 19 and 20 to the mixing chamber, their upper ends being connected to the tanks 13 and 14 by the respective siphoning sections 21 and 22 which extend into the tanks and terminate adjacent their bottoms, the elevation of the containers above the fire hazard providing a sufficient head for gravity flow of the solutions to the mixing chamber for its practical operation. These siphonic connections are "dry" and

"valveless" and are main connections in the sense that they conduct the whole of the component solutions and are devoid of any collateral pipes on which their action is dependent.

As the means for starting the siphonic flow, we prefer to adopt pressure means, the cartridge illustrated, or other pressure unit, whether or not explosive, of sufficient capacity only or kept in operation only long enough, to fill the siphons. This is best done by a temporary pressure impulse sufficient to raise each solution to the top of its siphon. Where automatic operation is required, we consider it best to use a gas generator adapted to be brought into action by abnormal heat adjacent the fire hazard, the gases thereupon generated being conducted in the system illustrated to the tanks 13 and 14 for exerting on the solutions therein enough pressure to start the siphons. In the preferred form of our installation we provide the gas generator 23, which comprises gas producing means of the type disclosed in the patent to Frederick C. Bargar, No. 1,422,406, granted July 11, 1922, and consisting of a gas chamber 24 having a combustible cartridge 25 in one end and a free weight 26 in the other and having in its walls a plurality of gas-exit perforations 27. A self-contained energy unit is thus provided which being of limited capacity is operative only through a period of short duration. The gas producing means which is made up as a separate refill is shown as loose in an enclosing tubular casing 28, closed at one end by the cap 29, and connected at its other end to a flexible tubing 30 attached to the cap 31, the casing 28 with the enclosed gas generating means being normally suspended in horizontal position, as shown in full lines in Figures 1 and 2 of the drawings, by a fusible link 32, whose ends are attached respectively to the cap 29 and the ceiling 33 or other support. The gas generator 23 is in communication with the solution tanks 13 and 14, by the gas line 34 which has one end supported by one or more brackets 35 and

connected to the flexible tubing 30 and its other end connected by means of the pipe sections 36 and 37, to the tank inlets 38 and 39 which may be provided with gauges 40 and 41.

For the purpose of opening the tanks 13 and 14 and the lines 36 and 37 to atmosphere after the pressure means has started flow of the solutions through the siphonic connections, in order to equalize pressure, in the containers and said connections, a check valve 42, located in the gas line 34 is arranged to be closed by the starting pressure from the gas generator 23 and to be opened by atmospheric pressure when the pressure in the tanks falls below atmospheric pressure. For the purpose of preventing any departure from normal temperature in the gas line 34 from initiating movement of the solutions through the siphoning lines, and in order to prevent any vapor pressure of the solutions in the tanks from building up sufficiently to start such flow, we further preferably provide a bleeding or breathing valve 43 in the gas line 34, the said valve conveniently taking the form of a T connection provided with a Monel filter cloth sufficient to permit the normal breathing of the system and insufficient to interfere with the normal operation of the pressure means. But it will be evident that one small breather hole will serve the purpose of both valves.

The operation of the system is as follows: Upon the occurrence of a fire in the dip tank 10 the link 32 will be fused and the gas generator 23 will drop to substantially vertical position as shown in dotted lines in Figures 1 and 2, the weight 26 falling upon the end of the cartridge 25 and setting off the same, the gases generated moving into and through the casing 28 and by the flexible piping 30 into the pressure line 34 and thence to the tanks 13 and 14, exerting pressure on the solutions therein to fill the siphons and start siphonic flow through the solution delivery lines 15 and 16. When the starting impulse is expended air enters by valve 42 or by a breather hole to replace the solutions, as, once the siphonic action has been started, they flow thereafter by gravity into the mixing chamber 11 where the usual intermixture of the solutions with foam production takes place and from which the foam is expelled into the dip tank 10 and over the burning surface of the liquid therein.

While we have shown our device in the preferred form, it will be obvious that many changes and modifications may be made in the structure disclosed without departing from the spirit of the invention, defined in the following claims:

1. A foam protecting installation comprising an acid solution tank, a basic solution tank, a mixing chamber below said tanks,

valveless siphon delivery pipes for connecting the respective tanks to the mixing chamber, means operative only through a period of short duration for initiating the flow in both said siphon delivery pipes, the flow thereafter being predominantly a gravity flow and means opening the tanks to the atmosphere sufficiently to compensate the delivery of liquid therefrom.

2. A foam protecting installation comprising an acid solution container and a basic solution container elevated above the fire hazard, a mixing chamber, normally open siphon delivery pipes connecting each container with the mixing chamber and means for initiating solution flow through said pipes by temporary pressure impulse.

3. A foam protecting installation comprising an acid solution container and a basic solution container both elevated above the fire hazard, a mixing chamber, normally open siphon delivery pipes connecting each container with the mixing chamber, means for initiating solution flow through said pipes, and means for admitting atmosphere to the tanks to compensate the delivery of liquid therefrom.

4. In a gravity operated fire extinguishing system, an acid solution container, a basic solution container, a mixing chamber, siphonic connections between each of said containers and said mixing chamber, both said containers being elevated above the fire hazard to provide a sufficient head for gravity flow of the solutions to the mixing chamber for the practical operation of the latter, and means for altering only temporarily pressure conditions in the system to initiate siphonic flow thereafter maintained by gravity.

5. Fire extinguishing apparatus comprising an acid solution container and a basic solution container elevated above the fire hazard, a mixing chamber, siphonic connections between each of said containers and said mixing chamber, a cartridge connected to both said containers, and means to set it off.

6. In a gravity operated fire extinguishing system, an acid solution container, a basic solution container, a mixing chamber, siphonic connections between each of said containers and said mixing chamber, both said containers being elevated above the fire hazard to provide a sufficient head for gravity flow of the solutions to the mixing chamber for the practical operation of the latter, means brought into play by abnormal heat adjacent the fire hazard for altering only temporarily pressure conditions in the system to initiate siphonic flow thereafter maintained by gravity.

7. Fire extinguishing apparatus comprising an acid solution container and a basic

solution container elevated above the fire hazard, a mixing chamber, normally open siphonic connections between each of said containers and said mixing chamber, and means for altering pressure conditions in the system to start siphonic flow, thereafter maintained by gravity without predominating explosive action of the starting means.

8. In a fire extinguishing apparatus of the type in which normally stored chemical component solutions are intermixed in time of fire for the production of a fire extinguishing medium, tank means for separately holding the component solutions, a mixing station, solution lines for independently conducting the component solutions to the said mixing station, the tank means being located at an elevation above the mixing station to provide a gravity head in the solution lines, and means for initiating movement of the solutions through the said lines, feeding of the solutions after the initiated movement thereof being accomplished by the gravity head; the said means including provisions automatically controlled by fire conditions for exerting pressure on the solutions in the tank means.

9. In a fire extinguishing apparatus of the type in which normally stored chemical component solutions are intermixed in time of fire for the production of a fire extinguishing medium, tank means for separately holding the component solutions, a mixing station, solution lines for independently conducting the component solutions to the said mixing station, the tank means being arranged at an elevation above the mixing station to provide a gravity head in the solution lines, the said solution lines being connected in siphoning relation with the tank means and means for initiating movement of the solutions through the said lines, the said means including provisions automatically controlled by fire conditions for exerting pressure on the solution levels in the tank means.

10. In a fire extinguishing apparatus of the type in which normally stored chemical component solutions are intermixed in time of fire for the production of a fire extinguishing medium, a mixing chamber, tank means for separately holding the component solutions located at an elevation above the mixing chamber, solution lines for independently conducting the component solutions to the said mixing chamber, the said solution lines being connected in siphoning relation with the tank means and means for initiating movement of the solutions through the said lines including provisions independent of the said mixing chamber and automatically controlled by fire conditions for exerting pressure on the solution levels in the tank means.

11. In a fire extinguishing apparatus of

the type in which normally stored chemical component solutions are intermixed in time of fire for the production of a fire extinguishing medium, a mixing chamber, tank means for separately holding the component solutions located at an elevation above the mixing chamber, solution lines for independently conducting the component solutions to the said mixing chamber, the said solution lines being connected in siphoning relation with the tank means and means for initiating movement of the solutions through the said lines including a gas generator effective when brought into operation to cause the solutions to fill the siphons and thus initiate siphonic action.

12. In a fire extinguishing apparatus of the type in which normally stored chemical component solutions are intermixed in time of fire for the production of a fire extinguishing medium, a mixing chamber arranged for protecting a fire hazard, tank means for separately holding the component solutions, solution lines for independently conducting the component solutions to the said mixing chamber and connected in siphoning relation with the said tank means, the tank means being located at an elevation above the mixing station for providing a gravity head in the solution lines and means for initiating movement of the solutions through the said lines, the said means including a gas generator located adjacent the said fire hazard and pressure lines connecting the gas generator to the said tank means and means permitting automatic operation of the said gas generator upon the occurrence of a fire.

13. In a fire extinguishing apparatus, tank means for holding a fire extinguishing solution, solution distributing means connected to the tank means for conducting the solution to a discharge station, the tank means being located at an elevation above the discharge station to provide a gravity head in the distributing means and a device operating by combustion for initiating movement of the solution through the said distributing means, feeding of the solution after the initiated movement thereof being accomplished by the gravity head, the said means including provisions automatically controlled by fire conditions for exerting pressure on the solution in the tank means.

14. A foam protecting installation of the dry type comprising a solution tank, a chamber having an opening for admission of a solution mutually reactive with the solution in said tank to produce a foam, valveless main delivery siphoning means operating independently of said mutually reactive solution for conducting solution from said tank to said chamber into contact therein with said mutually reactive solution and thereby producing the foam stream,

and a source of energy operative only through a period of short duration for starting the siphonic flow through said valveless siphonic means, said flow continuing thereafter predominantly a gravity flow.

15. A foam protecting installation of the dry type comprising a solution container, a chamber having an inlet for a solution mutually reactive with the solution in said tank to produce a foam, valveless main delivery siphonic means for delivering solution from said container into contact in said chamber with said mutually reactive solution and thereby producing the foam stream, 15 and a gas producing cartridge of limited capacity operative only through a period of short duration for starting the siphonic flow through said valveless siphonic means, said flow continuing thereafter predominantly 20 a gravity flow.

16. A fire extinguishing installation comprising a tank for fire extinguishing medium above the fire hazard, main delivery means therefor normally open and empty all the 25 way to the fire hazard and including siphonic means, and heat-actuated means putting the fire extinguishing medium in the tank under pressure for a short period only for initiating siphonic action therein, said 30 action being thereafter maintained predominantly by gravity, and means opening the tank to the atmosphere sufficiently to compensate the delivery of liquid therefrom.

17. A fire extinguishing installation according to claim 16, in which the siphonic-action-initiating means is wholly independent of fire emergency discharge from the system.

18. A foam protecting installation comprising A and B solution containers, one of which is above the fire hazard, means operating independently of one of said solutions for conducting the other from its container into contact therewith and for delivering foam to the fire hazard, said means being normally open and empty all the way to the fire hazard and including siphonic means, and means for initiating siphonic action therein, said action being thereafter 45 maintained predominantly by gravity, and means opening the container of said solution to the atmosphere sufficiently to compensate the delivery of liquid therefrom.

19. In fire extinguishing apparatus a container for fire extinguishing charge, a casing for communication therewith, and a gravity-operated gas producer loose therein and made up as a separate refill unit having a casing containing both a cartridge and operating means therefor, one of which is free to fall onto the other to set off the cartridge when the casing approaches the vertical.

20. A foam protecting installation according to claim 18, in which the siphonic-action-

initiating means is wholly independent of fire emergency discharge from the system.

21. In a fire extinguishing apparatus, a container for fire extinguishing charge, a suspended casing exterior to the container and adapted to have its interior in communication with that of the container, a cartridge in the casing, and means for setting it off on dropping of the casing.

22. A foam protecting installation of the dry type comprising containers for mutually reactive solutions, valveless siphoning means constituting the main solution delivery means for bringing one of said solutions into contact with the other to produce the foam stream, and a self-contained energy unit of limited capacity operative only through a period of short duration for starting the siphonic flow through said valveless siphonic means, said flow continuing thereafter predominantly a gravity flow, and means for calling said energy unit into activity.

23. A foam protecting installation of the dry type comprising containers for mutually reactive solutions, valveless siphoning means constituting the main solution delivery means for bringing one of said solutions into contact with the other to produce the foam stream, and a self-contained energy unit of limited capacity operative only through a period of short duration for starting the siphonic flow through said valveless siphonic means, said flow continuing thereafter predominantly a gravity flow, and means brought into play by abnormal heat adjacent the fire hazard to set the energy unit into operation.

24. In fire extinguishing apparatus, a container for fire extinguishing charge, a dry casing for communication with said container, movable with respect thereto and having therein a gas producer including a cartridge and means to set it off on relative movement of said cartridge and means resulting from movement of the dry casing with reference to the container.

25. In fire extinguishing apparatus, a movable casing, and a gravity-operated gas producer loose therein and made up as a separate refill unit having a casing containing both a cartridge and operating means therefor, one of which is free to fall onto the other to set off the cartridge when the casing approaches the vertical.

26. In a fire extinguishing apparatus, a container for fire extinguishing charge, a suspended casing exterior to the container, and piping connecting the interiors of the container and casing, a gas producer loose in the casing and made up as a separate refill unit having movable relatively therein a cartridge and means for setting it off on dropping of the casing.

27. In a fire extinguishing apparatus, a

container for fire extinguishing charge, a suspended casing exterior to the container, and piping, in part flexible, connecting the interiors of the container and casing, a gas producer loose in the casing and made up as a separate refill unit having movable relatively therein a cartridge and means for setting it off on dropping of the casing, and means operated by abnormal heat adjacent the fire hazard for permitting the casing to drop.

Signed at New York city, in the county of New York and State of New York, this 31st day of March, A. D. 1922.
